WATER PRESSURE DRAIN CLEANING NOZZLE

Bernard M. Warsinger, Orange, Calif., assignor to Stanley E. Hanson and Richard T. Post, Anaheim, and Thomas P. Mahoney and George E. Schick, Santa Monica, Calif., fractional part interest to each

Filed Apr. 21, 1972, Ser. No. 246,506

Term of patent 14 years

Int. Cl. D23—01

U.S. Cl. D23—34

Fig. 1.

Fig. 2.

Fig. 3.

FIG. 1 is a side elevational view of a water pressure drain cleaning nozzle embodying my new design;

FIG. 2 is a top plan view thereof; and
FIG. 3 is a bottom plan view thereof.

I claim:

The ornamental design for a water pressure drain cleaning nozzle, as shown.
